HOLDER FOR CASSETTES OR THE LIKE

Hormoz Rafaat, 2632 Seaview, Corona del Mar,
Calif. 92625

Filed May 1, 1972, Ser. No. 249,481

Term of patent 14 years

Int. Cl. D6—04

U.S. Cl. D6—190

Fig. 1

Fig. 2

FIG. 1 is a perspective view of a holder for cassettes or the like embodying my new design.

FIG. 2 is a bottom plan view of the holder for cassettes or the like.

FIG. 3 is a side elevational view of the holder for cassettes or the like illustrating the side of the holder which is hidden from view of FIG. 1.

FIG. 4 is a perspective view of the holder for cassettes or the like taken from the rear.

I claim:

The ornamental design for a holder for cassettes or the like, substantially as shown.
